George G. Riland
INVENTOR
BY Victor J. Evans

WITNESS:

John Donoran

ATTORNEY

UNITED STATES PATENT OFFICE.

GEORGE G. RILAND, OF MIFFLINBURG, PENNSYLVANIA.

HARNESS ATTACHMENT.

Application filed August 5, 1927. Serial No. 210,917.

This invention relates to harness attachments, and its general object is to provide buckles that are adapted to securely receive driving lines and the like of a set of harness and in a manner whereby any number of horses up to and including eight in a team can be controlled with a single pair of lines in the hands of the driver.

A further object of the invention is to provide driving line buckles that are simple in construction, inexpensive to manufacture, can be associated with driving lines or the like in an easy or expeditious manner and will take the place of a plurality of buckles and the like as well as to enable the driver of the team to properly, accurately and efficiently control the team with a single pair of lines.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a fragmentary side elevation of the buckles forming the subject matter of the present invention and showing their application to the lines of a set of harness for a team of horses.

Figure 2 is a bottom plan view of one of the buckles.

Figure 3 is a sectional view taken on line 3—3 of Figure 2.

Figure 4 is a bottom plan view of the other buckle which cooperates with the buckle as shown in Figure 2.

Referring to the drawings in detail the buckle which I term the hooking-up or main buckle includes a frame comprising longitudinal substantially tapered side members 1 and 2 which are provided with substantially rounded ends as best shown in Figure 3 of the drawings. Disposed at the small end of the side members and integrally formed therewith are spaced parallel cross bars 3 and 4, while extending from one longitudinal edge of the side members 1 and 2 are cross strips 5 and 6 which are arranged in spaced relation and have their outer portions curved to follow the curvature of the

edge 7 of the side members. Arranged between the enlarged end of the side members and the cross strip 6 is an intermediate bar 8 which is rectangular in formation as shown, and disposed upon the opposite side of the side members and at the enlarged ends thereof is a plate 9 which is provided with a plurality of spaced parallel rounded openings 10.

In Figure 4 I have illustrated the other buckle which I term a splicing buckle and this buckle is adapted to fix a snap hook to the ends of a check line as best shown in Figure 1 and includes arcuate shaped side members 11 and 12 which are secured together by a plurality of equi-distantly spaced cross bars indicated respectively by the reference numerals 13, 14 and 15. Disposed adjacent one end of the side members 11 and 12 and in opposed relation with respect to the cross bars 13, 14 and 15 is a strip 16 arranged at one end of the side members as shown in Figure 4, while a plate 17 is disposed at the opposite end thereof and said plate is provided with a centrally disposed rounded aperture 18.

In Figure 1 I have illustrated the application of my buckles with a set of harness which is adapted for a team of horses and the hooking-up or main buckle is adapted to receive one of the two driver's lines, which as shown is indicated by the reference numeral 19, and this line is passed through the bar 8, about the cross strips 5 and 6 and between the cross bars 3 and 4 as shown. By this arrangement, the line 19 will be secured to the buckle for movement thereof as will be apparent, and looped about a rounded in cross section bar 20 in a manner to be disposed between the bar 8 and plate 9 is a strap 21 which has its looped portions fixed in the splicing buckle as shown and is disposed between the strip 16 and cross bar 13, thence overlies the cross bar 14 and is inserted between the cross bar 15 and plate 17. The plate 17 has received in its aperture, a snap hook while received in one of the apertures 10 of the plate 9 is a snap hook which has secured thereto a looped line with its looped portions secured together by another splicing buckle.

From the above description and disclosure of the drawings, it will be obvious that my buckles can be associated with a set of harness for any number of horses in a team up to and including eight, whereby the team

can be controlled by a single pair of drive lines, one of which is indicated by the reference numeral 19 in Figure 1. The remaining lines are of course adapted to be associated 5 with the respective bits of bridles of one or more horses in the team.

It is thought from the foregoing description that the advantages and novel features of my invention will be readily apparent.

10 I desire it to be understood that I may make changes in the construction and in the combination and arrangement of the several parts, provided that such changes fall within the scope of the appended claims.

15 What I claim is:

1. A buckle of the character described comprising side members, spaced bars arranged adjacent one end of said side members, a bar disposed adjacent the opposite 20 end thereof, intermediate cross means between the end bars and disposed at one side

of said side members, said intermediate cross means being adapted for cooperation with the spaced bars and bar second mentioned for securing straps to the buckle and an 25 apertured plate at the opposite side and said opposite end.

2. A buckle of the character described comprising side members, cross members arranged between the ends of said side members and at one side thereof, cross bars disposed at one end of said side members, an intermediate bar disposed adjacent the opposite end and the cross members respectively, an apertured plate at said opposite end and 30 at the side opposite the side members and a rounded in cross section bar arranged between the ends of said side members and adjacent the cross members.

In testimony whereof I affix my signature.

GEORGE G. RILAND.
